CLAIM

The ornamental design for an audible window and door intrusion alarm, as shown and described.

DESCRIPTION

FIG. 1 is a front and left side isometric view of an audible window and door intrusion alarm showing my new design;

FIG. 2 is a top plan view thereof;

FIG. 3 is a right side elevational view thereof; and

FIG. 4 is a top, front, right side isometric view thereof with the door shown in broken lines for illustrative purposes only.

Fig. 1
